UNITED STATES PATENT OFFICE

2,577,104

DRIER SAFETY CONTROL

Frank L. Butler, Americus, Ga., assignor to General Electric Company, a corporation of New York

Application May 16, 1950, Serial No. 162,317

2 Claims. (CL 34—55)

1

This invention relates to a clothes drier of the type used in domestic laundries, and more particularly to a control device to prevent overheating in a clothes drier.

In motor driven clothes driers, the clothes are ordinarily tumbled about in a drum which rotates in a heated atmosphere. The conventional means for raising the air temperature within the casing accommodating the drier is by electrically energized or controlled heater means disposed in a duct system through which air flow is enforced by a motor driven fan or the like. Said duct system may discharge into the room in which the drier is located and it is usual to employ a screen or other trap to prevent discharge of lint. Said trap will, after continuous use, collect enough lint to impede the free flow of air through the duct system. Driers conventionally employ a thermostat to disconnect the power source when the temperature within the drier rises above a predetermined level. Should the thermostat fail to operate, as is often the case, the air temperature in the casing might build up dangerously, and abnormal turbulence resulting from faulty air circulation may allow some lint to settle on the heater and ultimately ignite.

The principal object of this invention is to provide means for automatically disconnecting the power source from the drier whenever the quantity of air flowing through the drier drops below a predetermined minimum, thereby providing back-up protection for the thermostat.

Another object of this invention is to provide means which will serve to remind the operator of the drier that the lint collecting screen should be cleaned periodically.

A further object of this invention is to provide means to disconnect the power source from the drier if a stalling load should be applied to the drive motor.

In the attainment of the foregoing objects, an important feature of this invention lies in an air-pressure-sensitive switch, electrically operated switching means effective to control the power input to the drier, and a lint collecting screen. The air-pressure-sensitive switch is so adjusted that whenever the air flow through said screen is below a predetermined level, the air switch will be closed, and said electrically operated switching means will be energized, thereby opening the power circuit to the drier.

For a better understanding of this invention, attention is now directed to the following description and the accompanying drawing and also to the appended claims in which the features of the invention believed to be novel are particularly

2

pointed out. Fig. 1 is a side section elevation of a typical drier utilizing this invention; Fig. 2 is a side elevation of the lint detector with the contacts open; Fig. 3 is a rear elevation of the lint detector with the contacts open; Fig. 4 is a side elevation of the lint detector with the contacts closed; and Fig. 5 is a typical drier control circuit utilizing this invention.

Referring to Fig. 1, the insulated casing 1 of the drier 2 has entrance louvers 3 and exit louvers 4 to permit passage of air through drier 2. An electrically energized heating means 5 is disposed near entrance louvers 3. Casing 1 also has a door 6 in the front thereof through which wet clothes 15 may be passed into the foraminated tumbler 7. Tumbler 7 is mounted upon shaft 8 which is suitably journaled in bearings provided in the rear wall of casing 1, shaft 8 being connected to a drive motor 9 by a speed reduction means such as a system of belts and sheaves or the like. An impeller fan 10 is directly connected to the motor 9 by a shaft 11. The fan 10 is positioned at the opening of a pressure compartment 11a which substantially encloses the motor 9 and has in its upper edge near the casing a slot (not shown). The air within the compartment 11a is pressurized by the fan 10 and escapes through the slotted opening in the form of a sheet along the sides of the casing, passing across the heater 5 and filtering into the foraminous drum 1. This construction is more fully disclosed in the co-pending application of John H. Robinson and Paul L. Paulson for Laundry Dryer, Serial No. 209,280, filed February 3, 1951, and assigned to the General Electric Company, assignee of the present application. A suitable duct system 12 is provided to channel the humid lint-bearing air from the tumbler 7 through a removable lint-catching screen 13 and through exit louvers 4. Trackways 14 are provided in duct 12 to serve as guides for screen 13. An air-pressure-sensitive switching mechanism 15 is disposed in duct 12 between screen 13 and exit louvers 4.

Referring to Fig. 2 and Fig. 3, air-pressure-sensitive switch 15 consists of a vane 16 mounted on a pivot 17 in duct 12. Mounted on the lower end of vane 16 is a contact 18 cooperating with the contacts 19 mounted on the bottom of duct 12. Contacts 19 also serve as a stop for vane 16 when it tends to move in a clockwise direction. An adjustable weight 20 mounted on the upper end of vane 16 partially balances the torque due to contact 18 when vane 16 is in a horizontal position, and it adds to the torque due to contact 18 when vane 16 is in a vertical position or slightly turned in the contact-opening direction. The

stop bar 21 prevents vane 16 from being turned too far in the contact-opening direction. Referring to Fig. 5, a source of electric power is connected to drier 2 through the supply conductors 22. Supply conductors 22 are connected to drier 2 by depressing the push button switch 23 which energizes the relay 24 closing the normally open contacts 25 and 26. The timer 21 is adjusted by the operator to disconnect motor 9 and heater 5 after a desired period of operation. The thermostat 28 is adjusted to disconnect motor 9 and heater 5 if the temperature inside the drier rises above a predetermined level. The door switch 29 disconnects motor 9 and heater 5 any time door 6 is opened. A centrifugal switch 30 removes the motor starting field windings 31 from the circuit and switches the relay 32 into the circuit when motor 9 comes up to a predetermined operating speed. When relay 32 is energized, it closes the normally open contacts 33 and 34 connecting lint detector 15 to the relay 35, and connecting heater means 5 to the power source respectively. When relay 35 is energized the normally closed contacts 36 and 37 are opened, thereby disconnecting heater means 5 and motor 9 from supply conductors 22.

When push button switch 23 is depressed, relay 24 is energized thereby closing normally open contacts 25 and 26 and connecting motor 9 to the power source if door switch 29 is closed. At this time centrifugal switch 30 is in the starting position. When motor 9 comes up to the predetermined operating speed, centrifugal switch 30 disconnects the starting winding 31 and connects relay 32, thereby closing normally open contacts 33 and 34 and connecting relay 35 to lint detector 15 and heating means 5. Fan 10 draws fresh air into drier 2 through entrance louvers 3. Said air passes over heating means 5 in the manner previously explained and through foraminated tumbler 7 where it acquires moisture and lint from the clothes therein. The humid, lint-bearing air is then drawn downward into duct system 12 and forced through screen 13, air-pressure-sensitive switch 15, and exit louvers 4 into the outer room. As long as the air flowing through air-pressure-sensitive switch 15 is above the predetermined level, vane 16 will be held in the horizontal position as shown in Fig. 2. When stalling load is applied to motor 9 or when screen 13 becomes obstructed so that the air flow through switch 15 falls below the predetermined minimum, vane 16 will gradually turn in the contact-closing direction until counterweight 20 passes over pivot 17 at which time vane 16 will move rapidly in the contact-closing direction until cooperating contacts 18 and 19 are closed. When cooperating contacts 18 and 19 close, relay 35 is energized and normally closed contacts 36 and 37 are opened, de-energizing heating means 5 and relay 24 which in turn opens contacts 25 and 26 disconnecting the remaining drier circuit from the supply conductors 22. When centrifugal switch 30 turns to the starting position, relay 32 releases contacts 33 and 34. Drier 2 is now in its normal inoperative condition.

If the air flow through screen 13 is below the predetermined level when relay 32 is energized, cooperating contacts 18 and 19 remain closed, contacts 33 are closed by relay 32 and supply conductors 22 are disconnected from the drier circuit as hereinbefore described.

While the present invention has been described by reference to particular elements thereof, it will be understood that this is by way of illustration of the principles involved and that those

skilled in the art may make many modifications in the arrangement and mode of operation. Therefore, I contemplate by the appended claims to cover any such modifications as fall within the true spirit and scope of this invention.

What I claim as new and desire to secure by Letters Patent of the United States is:

1. In a clothes drier or the like, having a casing, a foraminated clothes receiving drum mounted for rotation in said casing, means including an inlet passage and an outlet passage in said casing for permitting air circulation therethrough, a removable lint-collecting screen in said outlet passage to trap lint which may be suspended in said air flow, electrically operated heater means within said casing for raising the air temperature therein, a motor for rotating said drum, a fan driven by said motor for discharging heated air from said casing at a predetermined rate, and circuits for respectively connecting said motor and said heater energizing means to a source of electrical energy, the improvement in electrical control means for said circuits comprising a relay having normally open contacts in series in said motor circuit, a circuit for energizing said relay to close said contacts, a relay having normally open contacts in series in said heater energizing circuit, a circuit for energizing said relay to close said contacts, a third relay having normally closed contacts respectively in the energizing circuit of said first relay and in the said heater energizing circuit, means for connecting said last named relay to a source of electrical energy to open said normally closed contacts upon reduction in air flow through said screen, including fixed contacts and a movable contact in series in said third relay energizing circuit and a pivotally mounted vane carrying said movable contact and disposed downstream of said screen in the path of discharging air flow to be rotated thereby to maintain an open circuit condition under normal air flow conditions, said vane being counterweighted to cause said last-named contacts to close upon reduction in air flow through said screen as aforesaid.
2. In a clothes drier or the like, having a casing, a foraminated clothes receiving drum mounted for rotation in said casing, means including an inlet passage and an outlet passage in said casing for permitting air circulation therethrough, a removable lint screen in said outlet passage to trap lint which may be suspended in said air flow, electrically operated heater means within said casing for raising the air temperature therein, a motor for rotating said casing, a fan driven by said motor for discharging heated air from said casing at a predetermined rate, and circuits for respectively connecting said motor and said heater energizing means to a source of electrical energy, the improvement in electrical means for said circuits comprising a relay having holding contacts and having normally open contacts in series in said motor circuit, a circuit for energizing said relay to close said contacts, a relay having normally open contacts in series in said heater energizing circuit, a circuit for energizing said relay to close said contacts in response to speed of rotation of said motor, a third relay serially connected with normally open contacts operated by said second relay and having normally closed contacts respectively in the energizing circuit of said first relay and in the said heater energizing circuit, means for connecting said last-named relay to a source of electrical energy to open said normally closed

contacts upon reduction in air flow through said screen, including a fixed contact and a movable contact in series in said third relay energizing circuit and a pivotally mounted vane carrying said movable contact and disposed downstream of said screen in the path of discharging air flow to be rotated thereby to maintain an open circuit condition under normal air flow conditions, said vane being counterweighted to cause said last-named contacts to close upon reduction in air flow through said screen as aforesaid. 10
